(57) **CLAIM**

The ornamental design for a construction toy element, as shown and described.

DESCRIPTION

FIG. 1 is a perspective view from above and to one side of the new design for a construction toy element;

FIG. 2 is a top plan view thereof;

FIG. 3 is a bottom plan view thereof;

FIG. 4 is a right side elevation view thereof;

FIG. 5 is a left side elevation view thereof;

FIG. 6 is a front elevation view thereof; and,

FIG. 7 is a front elevation view thereof.

In the drawings, the regions containing dash-dot broken lines represent the bounds of the claim which form no part of the claimed design.

1 Claim, 7 Drawing Sheets(56)
